(57) **CLAIM**

The ornamental design for a pulse rate meter, as shown and described.

DESCRIPTION

FIG. 1 is a front, top, and left side perspective view of a pulse rate meter showing our new design;

FIG. 2 is a rear, bottom, and right side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The dashed broken lines shown in the figures are included for the purpose of illustrating portions of the pulse rate meter that form no part of the claimed design. The dot-dash broken lines shown in the figures define the bounds of the claimed design and form no part of the claimed design.
